UNITED STATES PATENT OFFICE.

HENRY A. WISE WOOD, OF NEW YORK, N. Y., ASSIGNOR TO THE CAMPBELL PRINTING PRESS AND MANUFACTURING COMPANY, OF SAME PLACE.

PRINTING-MACHINE.

SPECIFICATION forming part of Letters Patent No. 590,604, dated September 28, 1897.

Application filed August 24, 1893. Renewed March 18, 1897. Serial No. 628,227. (No model.)

To all whom it may concern:

Be it known that I, HENRY A. WISE WOOD, a citizen of the United States, residing at New York, in the county of New York and 5 State of New York, have invented a new and useful Improvement in Printing-Machines, of which the following is a specification.

The aim of this invention is to improve that class of presses which are known in the 10 art as "reciprocating bed" printing-presses; and it consists in the peculiar feeding or web-manipulating devices hereinafter described, and also of a perfecting form of such press.

The first part of my invention is applicable either to a single form of such press, in which the web is printed on one side only, or to a double form of such press, in which the web is printed upon both sides, and in the drawings I have illustrated both such arrangements.

Referring to the drawings and in detail, Figure 1 is a side elevation of a printing-machine of the character referred to with my improvements applied thereto. Fig. 2 is a 25 sectional diagrammatic view illustrating the bed in the center of its movement to the right or in impression. Fig. 3 is a view similar to Fig. 2, showing the bed out of impression at the right. Fig. 4 is a sectional diagrammatic view illustrating my improved reciprocating-bed web-perfected press; and Fig. 5 is a view similar to Fig. 4, illustrating a modification of the device shown in Fig. 4.

This invention consists, first, in providing 35 a reciprocating or traveling bed web-printing press with a peculiar feeding mechanism which will continuously feed the web into the press; also, which will preferably continuously feed the web out of the press, which will release or shift the web around the impression-cylinder to perform the feed, and also in the peculiar compensating device by which the movement of the web necessarily given during the printing operation will be compensated for.

My invention further consists of a perfecting form of traveling-bed web-printing press so arranged that an impression can be taken on the web both at the forward and backward 50 movements of the beds.

Referring to the device shown in the first three sheets of the drawings, 10 10 represent the usual side frames of a machine of the character referred to.

B represents the traveling bed, which is 55 mounted in suitable ways or guides on the side frames, and A represents the stationary revoluble impression-cylinder with which the traveling bed coacts.

The cylinder and bed driving mechanism 60 may be arranged in any of the desired ways common in the art. On the stationary frames 10 10 are secured suitable brackets 11 11, in which form-rollers, as FF FF, and distributor-rollers G G may be arranged, so that the 65 form placed upon the traveling bed B will receive the proper supply of ink, and ink may be given to the form-rollers by any of the usual mechanisms, as ink-tables or ink-fountains, not necessary here to show or describe 70 at length.

Secured on the bed B is a rack 12, which meshes with a gear 13, secured on the shaft 14 of the impression-cylinder A. This gear may be mounted on both sides of the impression-cylinder, if so desired. Also mounted on the shaft 14 of the impression-cylinder A are two gears or pinions 15 15, whose pitch diameters are one-half the diameter of the impression-cylinder. These gears or pinions 80 15 mesh with and engage racks 16 of the sliders 17, which are mounted so as to be capable of a horizontal movement on the main frames 10 10. These frames carry looping-rollers 18 and 19 at their outer ends, as shown, 85 around which the web is looped in opposite directions by the guides hereinafter described. By this means it will be seen that the looping-rollers 18 and 19 will move oppositely to the bed B and at one-half the speed thereof. 90 A guide, as 20 21, is arranged at each side of the stationary impression-cylinder, as shown.

The path of the web through the machine may be followed by reference to Fig. 2.

From the web-roll W, which may be mounted 95 at the end of the frames, the web is led in between the bite of the rollers 22, 23, and 24. These rollers are preferably continuously driven, as by the means hereinafter described, and therefore will serve as and constitute a 100

feeding mechanism adapted to continuously draw the web from the web-roll and feed the same to the machine. From these continuously-running rollers the web passes under 5 the looping-roller 25, as shown, then up over the guide-roll 26, which is journaled in the main frames 10, then around the horizontally-moving looping-roller 18, before referred to, then around a roller 27, which is journaled 10 in the main frames 10, over the guide 20, under the impression-cylinder A, over the guide 21, then around a guide 28, which is journaled in the main frames 10, then around the horizontally-moving looping-roller 19, before 15 referred to, and then around a roller 29, which is journaled in the frames 10 10.

From the roller 29 the web passes around the looping-roller 30, and the two looping-rollers 25 and 30 are operated, as by the mechanisms hereinafter described, so as to constitute a shifting mechanism which will shift or feed the proper length of web around the impression-cylinder A while the same is not in impression with the form, so that at the 25 next printing movement of the bed a fresh surface of the web can be printed.

From the looping-roller 30 the web is led out of the machine between the continuously-running rollers 31, 32, and 33. These rollers 30 are continuously driven, as by the gearing hereinafter described. It will thus be seen that these rollers serve as a feeding-out mechanism which will continuously feed the web out of the press. The gearing for operating 35 these various parts, before referred to, may be arranged as follows:

34 represents the driving-shaft, which may be suitably journaled in the main frames 10 and to which power may be applied by any 40 suitable means, not necessary here to describe at length.

Mounted on the shaft 34 is a pinion 35, which meshes with and engages a gear 36, which is mounted on a shaft 360, journaled 45 in the main framing, as shown. Also mounted on the shaft 360 are crank-disks 361, which carry crank-pins 37, and these crank-pins connect by pitmen or connecting rods 38 to a shaft 39. This shaft 39 may be journaled in 50 bearings 40, which are fitted in suitable ways 41 in the main frames, as shown. On this shaft 39 are arranged two gears 42, which mesh with and engage stationary racks 43, secured on the inside of the main frames, as 55 shown.

Fastened on the under side of the bed B are racks 44, into which the gears 42 mesh. One gear 42, arranged in the middle of the press, may be used, or two gears arranged 60 near the side frames may be used. By this means it will be seen that the bed B, as the parts are operated, will be smoothly and easily reciprocated.

Meshing with and engaging the gear 36 is 65 a gear 45, which is mounted on a suitable stud 46, mounted in the main framing. Meshing with and engaging this gear 45 is a gear

47, which is mounted on a suitable stud or short shaft 48, journaled in the main framing, as shown. On the outside end of this 70 shaft 48 is mounted a bevel-gear 49, which meshes with and engages a bevel-pinion 50, which is secured to the shaft 51, which shaft 51 is journaled in suitable bearings 52, secured to one of the frames 10, and which 75 shaft 51 extends nearly the entire length of the press, as shown. I use this shaft to drive the continuously-running feeding-in and feeding-out mechanism, and the gearing may be arranged as follows: On the left-hand end of 80 the shaft 51 is mounted a bevel-gear 53, which meshes with a bevel-pinion 55, mounted on the lower end of the shaft 56, which shaft 56 is vertically arranged and journaled in suitable brackets, as 54 and 57. On the upper 85 end of this shaft 56 is mounted a bevel-pinion 58, which engages and meshes with a bevel-pinion 59, mounted on the end of the feeding-in roller 23.

The feeding-in rollers 22, 23, and 24 are 90 geared together, so that as the middle roller is turned they will all be revolved together. By this means the feeding-in device is rendered continuous.

On the right-hand end of the shaft 51 is 95 mounted a bevel-gear 60, which meshes with and engages a bevel-gear 62, secured on the lower end of a vertically-arranged shaft 63, which shaft 63 is journaled in suitable brackets 61 and 64, secured to the frame of the 100 machine. On the upper end of this shaft 64 is mounted a bevel-pinion 65, which meshes with and engages a bevel-pinion 66, secured to the middle feeding-out roller 32.

The feeding-out rollers 31, 32, and 33 are 105 geared together, so that as the middle roller is revolved they will all revolve synchronously. By this gearing the feeding-out device is rendered continuous.

Meshing with and engaging the gear 47 is a 110 gear 660, which is mounted on a shaft 67, which shaft 67 is journaled in the main frames, as shown.

The gear 660 is made one-half the size of the gear 36, so that the same will turn twice 115 for every forward and backward movement of the bed B. Mounted on this shaft 67 are cams 68.

69 represents suitable yokes, which are preferably hung on the shaft 67, and which yokes 120 carry rollers 70 and 71, which engage the cam 68. Extending from the yokes 69 are arms 690 and 691. The arms 690 connect to bell-crank levers 75, which are mounted upon studs 76. The arms 691 of the yokes 69 connect to 125 suitable bell-crank levers 72, which are mounted upon studs 73, as shown. I preferably use two cams 68 on opposite sides of the press and two yokes, and such is the arrangement shown. However, if desired, one cam and 130 one yoke could be used, and instead of using studs 76 and 73 shafts could be used, which could be made to extend across the press, and on which shafts the arms which operate the

looping-rollers could be secured, and of course the gearing could be so arranged that this could be done.

The ends of the bell-crank levers 75 connect 5 to arms 77, which constitute a looping-frame, and which arms are suitably guided in the main frames.

The bell-crank levers 72 connect to suitable arms 74, which constitute a looping-frame, 10 and which arms 74 are suitably mounted in the main frames.

The looping feeding-in roller 25 is mounted in the arms 77, and the looping feeding-out roller 30 is mounted in the arms 74. By this 15 means it will be seen that the looping-rollers 25 and 30 will be oppositely moved up and down. This gearing constitutes a new and improved means for operating one or two looping-rollers. By this gearing and means 20 described it will be seen that the press may be properly operated.

In Fig. 2 the bed B and cylinder A are shown as in impression and the bed as moving to the right.

25 The web is looped horizontally at each side of the impression-cylinder around the horizontally-moving looping-rollers 18 and 19, as shown. As the bed moves to the right these looping-rollers 18 and 19 will move to the left, 30 and as they move at one-half the speed of the bed the proper amount of web will be paid out and allowed to run around the impression-cylinder A, so that the web around the impression-cylinder A will move in unison with 35 the bed B.

The web which is continuously drawn from the web-roll by the continuously-running feeding-in rollers is taken up by the looping-roller 25, and the web which is being fed out 40 of the press by the continuously-running feeding-out rollers is being supplied by the upward movement of the looping-roller 30. In other words, during the printing movement of the bed there is no advance of the web into or 45 out of the printing district proper, which district is bounded by the guide 26 on the one hand and by the guide 29 on the other hand. Now when the bed B moves out of impression with the cylinder A the looping-rollers 25 and 50 30 will be oppositely moved—that is, the looping-roller 25 will move upward and the looping-roller 30 will move downward—and, as shown, the looping-rollers are timed so as to have an equal upward-and-downward movement. This can be done by using a heart-shaped cam or cams. Thus the feeding or 55 resspacing of the web with regard to the printing mechanism takes place.

The bed B is shown out of impression in 60 Fig. 3. In this case the web fed into the press by the continuously-running rollers and the upwardly-moving looping-roller 25 is being drawn forward or shifted around the impression-cylinder A by means of the downward 65 movement of the feeding-out roller 30 and the continuously-running feeding-out rollers 31,

32, and 33. By this action the feed or shift of the web will take place around the impression-cylinder, so that when the bed next comes into contact with the impression-cylinder 70 a fresh portion of the web will be printed.

The action of the looping-rollers 18 and 19 may be said to be that of a compensating feeding mechanism—that is, it is a feeding mechanism which simply moves or adjusts the web 75 around the impression-cylinder to compensate for the movement of the bed, as to make proper printing the web has to move during the impression at the same speed as the bed. This horizontal disposition of the looping-rollers 80 presents a very neat, simple, and positive compensating feeding mechanism.

By the feeding mechanism before described it will be seen that the web is continuously fed into and fed out of the press, that the 85 movement of the bed is compensated for by properly moving the web, and that the web is delivered from the printing district, which is bounded by the guides 26 and 29, while the impression-cylinder is out of printing contact 90 with the form.

As shown, the bed is arranged so as to print both on its forward and backward movement, and although it is within the scope of my invention to make the bed print only on one 95 movement and to operate the members so that the other movement of the bed will not make an impression it is preferred to make an impression both ways. Thus I have invented a 100 very fast acting web-printing press.

My invention is of course applicable to a printing-press in which two traveling beds are used, and such an arrangement is shown in Figs. 4 and 5. In Fig. 4 I have shown two beds, as B B', arranged one above the other 105 and as geared together through the gear or gears on the impression-cylinder A, and a rack or racks 121, secured to the under side of the bed B'. By this mechanism the beds B and B' will move oppositely, but in the same time— 110 that is, the forms on the beds will be in impression at the same time and out of impression at the same time. The path of the web through this arrangement of the press may be arranged as follows: From the web-roll W 115 the web passes in through the continuously-running feeding-in rollers 100, 101, and 102, which serve to continuously draw and feed the web into the press. Then the web passes under the looping feeding-in roller 103, then 120 up over the stationary guide-roller 104 to the stationary guide-roller 105. Then the web is looped around the looping-roller 106. Then the same passes to the stationary guide-roller 107, under the impression-cylinder A, up 125 around the guide-roller 108, then around the guide-rollers 109 and 110 to the upper press.

Either or both of the guide-rollers 109 or 110 may be made adjustable in any of the usual manners to secure register of the web between the two presses. 130

From the guide-roller 110 the web passes to

the stationary guide-roller 111, then under the impression-cylinder A', then over the guide-roller 112 to the stationary guide-roller 113, then around the looping-roller 114, then 5 to the stationary guide-roller 115 up over the looping-roller 116, and then out of the press through the rollers 117, 118, and 119. These rollers 117, 118, and 119 are continuously driven, so as to continuously deliver 10 the web from the press. It will be noted that the web is oppositely looped around the looping-rollers 114 and 106; also, that the looping-rollers are actuated, as described in the previous device, from the reciprocating frames 15 17, and the lower looping-roller 106 may be mounted in suitable arms or brackets 120, extending from these frames 17. The upper bed B' carries a rack or racks 122, which mesh with a gear or gears secured on the sides 20 of the impression-cylinder A', similar to the gear or gears 13 of the previous device.

123 represents the driving-shaft, from which power is applied by means of pinion 124 to the gear 125, mounted on a shaft 126, and 25 this shaft 126 may carry crank-pins 127, similar to crank-pins 37 of the previous device, by which the beds will be actuated. It will be seen, as before stated, that the beds will be oppositely moved. This arrangement of 30 beds is substantially the same as that shown in the patent to Royal Cummings, No. 83,471, granted October 27, 1868; but my invention embraces an important improvement over what is shown in his patent in that by the 35 use of my invention I am enabled to print both on the forward and backward movements of the beds and by which I am enabled to continuously feed the web into and out of the press, whereby the capacity and 40 production of the press will be more than doubled.

The looping-rollers 103 and 116 may be mounted in suitable arms 132, which arms may carry suitable rollers 131, which may 45 bear upon cams 130, mounted on a shaft 129, which shaft 129 may be driven from the shaft 126, as by means of the gears 125 and 128.

The gear 128 is preferably made one-half the size of the gear 125, whereby the cams 50 130 will turn twice for each forward-and-backward reciprocation of the bed.

The rollers 131 are preferably held against the cams 130, as by means of springs 133.

The action of the press thus far described 55 is substantially the same as that of the previous device, except that instead of the web being printed on one side the same will be printed upon both sides or perfected. It is not necessary that the beds should be arranged 60 one directly over the other, as they can be arranged in many different ways. One of such different arrangements is shown in Fig. 5, in which the beds are shown as arranged in the same horizontal plane, end to end. 65 In this modification the web is slackened off from the web-roll W and fed into the press

between the four continuously-running feeding-in rollers 201, 202, 203, and 204. Then the web passes around the looping-roller 205, around the stationary roller 206, then around the compensating looping-roller 207, then 70 around the stationary roller 208, then to the middle of the press, around the roller 209, up over the guide 210, then around the guide 211, under the impression-cylinder A, around the 75 guide 212, back to the guide or roll 213, then under the impression-cylinder A', then up around the guide-roll 214, then to the guide-roll 215, then down under the compensating looping-roller 216, then around the stationary 80 roller 217, around the looping feeding-out roller 218, and then between the continuously-running feeding-out rollers 219, 220, and 221. These rollers 219, 220, and 221 are continuously driven to positively and continuously 85 feed the web out of the press. By this passage of the web it will be seen that the same will be printed and perfected substantially as before described.

The mechanism for driving these various 90 parts may be arranged as follows: 223 represents a driving-shaft which is geared by pinion 224 to a large gear 225. This large gear 225 carries a crank-pin 226, which crank-pin 226 has mounted thereon a block 227, which 95 engages a vertical slot of the slider 228, which slider 228 is mounted so as to be capable of a horizontal movement. This slider 228 may also be mounted, if desired, upon a block secured upon the shaft 232 of the gear 225. 100 This yoke 228 carries a rack 229, which meshes with an intermediate 230, which intermediate 230 meshes with a gear 231, which gear 231 meshes with a rack 44 of the bed B. The yoke or slider 228 also carries a rack 233, which 105 meshes with a gear 234, which gear 234 meshes with and engages the rack 222 of the bed B'. By this means it will be seen that as the shaft 223 is rotated the slider 228 will be reciprocated and the bed B will be moved or 110 reciprocated in opposite directions. To operate the compensating looping device, which consists of the looping-rollers 207 and 216, I mount gears 235 with the gear 234. These 115 gears 235 mesh with segments 236, which are mounted on a shaft 237. These segments connect by connections 238 to bell-crank levers 239, which are mounted on a shaft 240, and this shaft 240 has suitable connections to the looping-frame 241, which carries the looping compensating rollers 207 and 216. By 120 this means it will be seen that the compensating looping-rollers will be properly actuated so that the web will be properly moved around the impression-cylinders to compensate for the movement of the beds. The web-shifting looping-rollers 205 and 218 are mounted in a suitable frame 245, which frame has rollers 244, which engage cams 243, which 125 cams are mounted on a shaft 242, which is driven from any suitable part of the mechanism twice for each complete reciprocation 130

of the beds. Springs 246 are preferably used to keep the rollers 244 against the cams. By this means the looping-shifting-rollers will be properly actuated. Thus this mechanism 5 will perfect a web, making two impressions for each forward-and-backward movement of the beds. I may use either a single yoke 228 and a single set of gearing to drive the beds in opposite directions, but it is preferred to 10 use a double set of yokes, one near each side frame, and a double set of gearing to drive the beds. In these last two described devices it will be seen that the two impression-cylinders will rotate oppositely, whereby the web 15 can always properly run from one impression-cylinder to the other without any intermediate device being interposed in the path of the web between the two impression-cylinders. Thus it will be seen that I have greatly im- 20 proved the class of presses known in the art as "traveling-bed" presses, and my improvements consist, so far as the web-controlling devices are concerned, first, in providing a continuous feed-in of the web, and so far as 25 this continuous feed-in is concerned any delivery mechanism can be used in connection with the same without departing from the scope of the claims; second, in providing a continuous feed-out or delivery for the web, 30 and so far as this feed-out is concerned any feeding-in mechanism can be used in connection with the same without departing from the scope of the claims; third, in providing a horizontally-arranged compensating loop- 35 ing device consisting of two synchronously-moving looping devices.

I do not wish to be limited to the details herein shown, as many equivalent devices for the feeding mechanisms are known and can 40 be used and substituted by a skilled mechanic without departing from the scope of my in- 45 vention as expressed in the claims.

Having thus fully described my invention, what I claim, and desire to secure by Letters 45 Patent, is—

1. The combination in a web-printing ma- 50 chine of a reciprocating bed, an oscillating cylinder coacting therewith, means for continuously feeding the web into and out of the press, a web-shifting mechanism, and a com- 55 pensating mechanism for moving the web in harmony with the bed, substantially as de- 60 scribed.

2. The combination in a web-printing ma- 65 chine of a reciprocating bed, an oscillating cylinder coacting therewith, suitable web- guides, means for continuously feeding the web into the press, means for controlling the web so that during impression the same will move forward and backward with the bed, and a suitable delivery mechanism, substan- 70 tially as described.

3. The combination in a web-perfecting printing-press of two reciprocating beds, an 75 oscillating cylinder coacting with each bed, suitable web-guides, means for feeding the

web continuously into the machine, means for moving the web forward or backward in harmony with the beds during impression, so that the beds will print on both forward and 70 backward strokes, and a delivery mechanism for the web, substantially as described.

4. The combination in a web-printing press of a stationary oscillating impression-cylinder, a traveling form-bed coöperating there- 75 with, a web-compensating device consisting of two loopers connected to move together in the same direction around which the web is looped in opposite directions, and a web-feed- 80 ing device, substantially as described.

5. The combination in a web-printing press of a stationary, oscillating impression-cylinder, a traveling form-bed coöperating there- 85 with, a web-compensating device consisting of two connected horizontally-moving loopers 90 around which the web is looped in opposite directions, means whereby these loopers will be moved oppositely to the bed at one-half the speed thereof, and a suitable web-feeding mechanism, substantially as described. 90

6. The combination in a web-printing press of a stationary, oscillating impression-cylinder, a traveling form-bed coöperating there- 95 with, a web-compensating device consisting of a frame mounted in the printing-press framework to move parallel with the bed, two loopers mounted in said frame around which the web is looped in opposite directions, means for moving said frame, and a web-feeding de- 100 vice, substantially as described.

7. The combination in a web-printing press of a stationary, oscillating impression-cylinder, a traveling form-bed coöperating there- 105 with, a web-compensating device consisting of two connected, synchronously-moving 110 loopers around which the web is looped in opposite directions, and a web-feeding de- 115 vice for properly feeding the web, consisting of means for synchronously feeding the web into and out of the press and for respacing 110 the web, substantially as described.

8. The combination in a web-printing press of an oscillating impression-cylinder, a recip- 120 rocating form-bed coacting therewith, a suit- 125 able web-compensating device, means for con- tinuously feeding the web into and out of the press, looping feeding-in and feeding-out rollers, said looping-rollers being mounted in arms, bell-crank levers connected to said arms, a rotating cam or cams, and connec- 130 tions from the rotating cam or cams to the bell-crank levers, substantially as described.

9. The combination in a web-printing press of two oscillating impression-cylinders, a re- 135 ciprocating form-bed coacting with each im- 140 pression-cylinder, a web-compensating device adapted to move the web to compensate for the movement of the form-beds, and a suit- 145 able web-feeding device, including means for continuously feeding the web into the press and for continuously delivering the web from 150 the press substantially as described.

10. The combination in a web-printing press of two oscillating impression-cylinders, a reciprocating form-bed coacting with each of said impression-cylinders, said form-beds moving in opposite directions, a web-compensating device for moving the web to compensate for the movement of the beds, a suitable web-feeding device adapted to respace the proper length of web through the press when the printing members are out of impression; means for continuously feeding the web into the press and means for continuously delivering the web from the press substantially as described.
15. 11. The combination in a web - printing press of two oscillating impression-cylinders, a reciprocating form-bed coacting with each cylinder, a web-compensating mechanism and a web-feeding device arranged to respace and shift the web as the beds reverse in either direction, whereby two perfected sheets will be printed for each reciprocation of the beds, substantially as described.
20. 12. The combination in a web-perfecting printing-press of two oscillating impression-cylinders arranged one over the other, a horizontally-reciprocating form-bed coacting with each impression-cylinder and printing on both forward and backward strokes, suitable web-guides, means for manipulating the web so that the same will run in harmony with the beds during the printing operation, and a web-feeding device arranged to respace and shift the web forward as the beds reverse in either direction, whereby two perfected sheets will be printed for each reciprocation of the beds, substantially as described.
25. 13. The combination in a web-perfecting printing-press of two oscillating impression-cylinders arranged one over the other, a reciprocating form-bed coacting with each cylinder, a web-compensating and a web-feeding device arranged to respace and shift the web as the beds reverse in either direction, whereby two perfected sheets will be printed for each reciprocation of the beds, substantially as described.
30. 14. The combination in a web - printing press of two oscillating impression-cylinders arranged one over the other, a reciprocating form-bed coacting with each cylinder, means for continuously feeding the web into the machine, a web - manipulating mechanism arranged to move the web in harmony with the beds as they move forward or backward, and a suitable delivery mechanism arranged to respace or shift the web as the beds reverse in either direction, the whole so arranged that two perfected printed sheets will be printed for each complete reciprocation of the beds, substantially as described.
35. 15. The combination in a web - printing press of two oscillating impression-cylinders, a reciprocating form-bed coacting with each of said impression-cylinders, a suitable web-compensating device, and a web-feeding de-

vice consisting of means for continuously feeding the web into and out of the press, and of two looping-rollers adapted to respace or shift the web through the press around the impression-cylinders when the printing members are out of impression, substantially as described.

16. The combination in a web - printing press of two oscillating impression-cylinders, a reciprocating form-bed coacting with each cylinder a web-compensating device consisting of looping devices, one arranged in the path of the web before the same passes to the first impression-cylinder, and the other arranged in the path of the web after the same passes from the second impression-cylinder, and a suitable web-feeding device, substantially as described.

17. The combination in a web - printing press of two oscillating impression-cylinders, a reciprocating form-bed coacting with each of said impression-cylinders, a web-compensating device consisting of web-looping devices arranged to form oppositely-arranged loops in the web before the same passes to the first impression-cylinder, and after the same passes from the second impression-cylinder, and a suitable web-feeding device, substantially as described.

18. The combination in a web - printing press of two oscillating impression-cylinders, a reciprocating form-bed coacting with each of said impression-cylinders, a web-compensating device consisting of devices adapted to form a loop in the web before the same passes to the first impression-cylinder, and a loop in the web after the same passes from the second impression-cylinder, means for moving said looping devices at one-half the speed of the form-beds, and a web-feeding device, substantially as described.

19. The combination in a web - printing press of two oscillating impression-cylinders, a reciprocating form-bed coacting with each of said impression-cylinders, a looping-frame actuated from one of said impression-cylinders at one-half the speed of the form-bed, said looping-frame carrying devices adapted to form a loop in the web both before the same passes to the first impression-cylinder, and after the same passes from the second impression-cylinder, and a web-feeding device, substantially as described.

20. The combination in a web - printing press of two oscillating impression-cylinders, a reciprocating form-bed coacting with each of said impression-cylinders, a horizontally-moving web-looping device adapted to move the web to compensate for the movement of the traveling form-beds, and a web-feeding device adapted both to feed the web continuously into and out of the press and to respace the web around the impression - cylinders when the printing members are out of impression, substantially as described.

21. The combination in a web - printing

press of two oscillating impression-cylinders, a reciprocating form-bed coacting with each of said impression-cylinders, continuously-running rollers for feeding the web into and out of the press, looping-rollers for respacing the web around the impression - cylinders when the printing members are out of impression, and horizontally-moving web-compensating devices adapted to move the web to

compensate for the movement of the form- 10 beds substantially as described.

In testimony whereof I have hereunto set my hand in the presence of two subscribing witnesses.

H. A. WISE WOOD.
